MANUAL RELEASE VALVE FOR RAILWAY
AIR BRAKE SYSTEMS

James T. Wade, Ogden, Utah

Application December 13, 1949, Serial No. 132,691

7 Claims. (Cl. 303—80)

1

This invention relates to railway air brake systems, and particularly to manual release valves as employed in such systems.

Railway air brake systems utilizing currently standard equipment embody manually-operable valves for enabling an airman at an inspection point, or a member of the train crew during a run, to exhaust air from the auxiliary reservoir without regard to provisions for automatic exhaust of air during normal operation of the system. Manual discharge or bleeding of air from the auxiliary reservoir becomes important when a train has pulled into a terminal and awaits inspection, with the engine disconnected from the rest of the train, as well as later, when the train has pulled away from the terminal and it is found that one or more of the cars still have the brakes set. In addition, there are various times during a run when the brakes on one or more of the cars may, for one reason or another, remain set, and must be released manually; for example, when a train is pulling back into the main track from a pass siding.

As presently constructed, the manual release valve of a railway air brake system requires an attendant to stand and hold the release valve handle until the required amount of air is exhausted from the auxiliary reservoir.

In instances of inspection, an airman must stand and hold such handle until all the air is exhausted, and repeat this, in turn, for each car of the train, which, obviously, involves a considerable waste of time, especially where there are two reservoirs to be emptied, auxiliary and emergency, as in the case of the Westinghouse "AB" freight brake equipment.

In instances where the train is moving, and it is found that the brakes on one or more of the cars are set, it is necessary for a trainman to run alongside the train, manipulating the release valve handle, until a sufficient amount of air is bled from the auxiliary reservoir to initiate brake cylinder exhaust. This is a dangerous proposition. Often, impediments alongside the track force the trainman to let go the handle and clamber aboard the rearmost car, where he can apply the air to stop the train. During the interim, of course, the set brakes on the particular car or cars cause the wheels to slide, resulting in flattening thereof.

I eliminate these objectionable features of existing equipment by interposing a delayed-return mechanism between the usual handle of a conventional manual release valve and the valve-actuating mechanism thereof. By means of the

2

resulting novel structural combination in railway air brake equipment, an attendant need merely give the handle a flip to open the release valve and to insure its remaining open for a predetermined time period. Closing of the valve is automatic following such given period.

Accordingly, principal objects of the invention are:

To greatly facilitate the manual release of 10 brakes in a railway air brake system.

To conserve the time of airmen during brake inspection, and of trainmen during runs.

To practically eliminate the danger associated 15 with the manual release of any brakes which may remain set at the commencement of a run.

To greatly reduce the occurrence of flat wheels in railway operation.

In accomplishing these objects I combine with 20 the customary manual release valve a suitable delayed-return mechanism.

A further object of the invention is to provide a simple and positive delayed-return mechanism admirably adapted for the purpose.

Additional objects and features of the invention 25 will become apparent from the following detailed description of the presently preferred embodiment thereof illustrated in the accompanying drawings.

In the drawings:

Fig. 1 represents an elevation of a typical installation embodying my invention;

Fig. 2, a horizontal section taken on the line 2—2 of Fig. 1;

Fig. 3, a vertical section through the structure 35 of Fig. 1, taken with reference to the line 3—3 of Fig. 2 and drawn to an enlarged scale; and

Fig. 4, a view corresponding to that of Fig. 3, but illustrating the release valve tripped to the extent of opening the port controlling exhaust of 40 the auxiliary reservoir.

Referring to the drawings, in which the invention is illustrated as part of the modern "AB" freight car brake equipment of a standard Westinghouse air brake system, the duplex release valve customarily provided in the service portion of such equipment comprises a valve housing 10 having operably positioned therein release checks 11 and 12 controlling exhaust passages 13 and 14, respectively, leading from the auxiliary and emergency reservoirs (not shown), respectively, of the equipment.

A plunger 15 having two upstanding stems 15a and 15b is provided for opening either one or both of the release checks 11 and 12, depending 55 upon how far the plunger is pushed upwardly on

any given actuation of the valve, it being noted that the check 11, which controls the auxiliary reservoir exhaust passage 13, is positioned at a lower level than check 12, and is opened by the stem 15a prior to the opening of check 12 by 5 stem 15b on the upward travel of plunger 15.

As normally constructed, the duplex release valve possesses a handle arranged for manual actuation in directly raising the plunger 15 the desired distance to open either one or both of the release checks 11 and 12. In operation, an airman or trainman must hold the handle in its actuated position until the requisite quantity of air is exhausted.

In accordance with my invention, I interpose a delayed-return mechanism between the said handle and the plunger 15, whereby the handle need merely be given a flip to insure exhaust of air for a given period of time. By pre-establishing to the time required for releasing the brakes, the period involved in return of the said mechanism to its original position (and, therewith, the plunger 15 and the actuating handle to their respective original positions) from the position concerned in opening the release check 11, a trainman who finds brakes remaining set when the train starts up need merely give the handle a quick flip to insure complete release of the brakes. An airman has the time he must spend in completely discharging the auxiliary and emergency reservoirs for inspection purposes greatly shortened.

While a variety of well-known delayed-return mechanisms may be easily adapted for the purpose by those skilled in the art, the particular mechanism which I here illustrate is especially advantageous for reasons hereinafter set forth.

As illustrated, see especially Figs. 3 and 4, the manually-actuated handle, indicated 16, depends from the lower open end of a cylindrical casing 17, which is rigidly but removably attached, as by threading, to the lower open end of an intermediate cylindrical casing 18 containing the delayed-return mechanism. Such intermediate casing 18 is rigidly but removably attached, also preferably by threading, to the customary depending annular portion 10a of valve housing 10.

Within intermediate casing 18 is defined a chamber 19 for a plunger 20, which is fixed intermediate the length of a push-rod 21. As shown, the upper end of the chamber 19 is closed by an end wall 18a of the casing 18, such end wall being integral with the casing proper. A central opening 22 is provided through such end wall 18a for passage of the upper portion of the push-rod 21. The lower end of the chamber 19 is closed by a plug made up of two annular pieces 23 and 24, between which is interposed an annular packing gland 25. The pieces 23 and 24 are threaded into the open upper end of casing 17, and serve to compress the packing gland 25 into sealing contact with the lower portion of push-rod 21.

The closed upper end of casing 18 is advantageously recessed to receive depending annular portion 10a of the valve housing 10 as a pressure agency for bearing tightly against washer 26 and compressing packing gland 27 into sealing contact with the upper portion of push-rod 21.

The chamber 19 is adapted to be filled with a hydraulic medium, as shown. A light grade of lubricating oil is preferred, the same being conveniently introduced through an opening which is normally closed by plug 28.

In permitting proper movement of the push-rod 21 when pushed upwardly by handle 16, adequate passage for rapid flow of the hydraulic

medium from the upper portion of chamber 19, above plunger 20, to the lower portion thereof, below plunger 20, is provided. As illustrated, a plurality of flow passages 29 extend vertically through plunger 20, the same being normally closed at their upper ends by balls 30 seating upwardly against annular lips 31 under the urge of springs 32 held in place by annular inserts 33. Thus, the balls 30 function as check valves, permitting flow downwardly through the passages 29, but preventing flow upwardly therethrough.

For delaying the return of push-rod 21 to its original position after being pushed upwardly by handle 16, restricted passage for relatively slow flow from the lower portion of chamber 19 to the upper portion thereof is provided. As illustrated, a predetermined limited degree of clearance 34 between plunger 20 and the walls of chamber 19 within which it operates, provides such restricted passage.

The upper end of push-rod 21 is positioned in abutting relationship with depending boss 15c of the valve-actuating plunger 15, while the lower end thereof is positioned in abutting relationship with the concave crown member 16a of handle 16. Such handle 16 is operably suspended from the lower open end of casing 17 by means of an annular insert member 35, which furnishes support for the crown member 16a. Such insert member 35 has a passage 36 therethrough sufficiently large in diameter to accommodate the required sideward movement of handle stem 16b when the handle member 16c is manually flipped to open either the release check 11, alone, or both the release checks 11 and 12, together.

In operation, handle 16 acts directly upon push-rod 21, which, in turn, acts upon the valve-actuating plunger 15. Upward travel of the push-rod is facilitated by downflow of the hydraulic medium through passages 29 of the delayed-return plunger 20, while the return of push-rod 21 to its original position is delayed by the necessity of the hydraulic medium below plunger 20 to return to the upper portion of chamber 19 by way of restricted passage 34.

The simple construction of the illustrated delayed-return mechanism, and the ease with which it may be disassembled and reassembled are distinct advantages. It is absolutely positive in operation, and requires little attention to maintain.

Furthermore, it is relatively inexpensive to manufacture and install.

Whereas this invention is here illustrated and described with respect to a certain presently preferred specific embodiment thereof, it should be understood that various changes may be made therein and various other forms may be constructed on the basis of the teachings hereof, by those skilled in the art, without departing from the protective scope of the following claims.

I claim:

1. In a railway air brake system, a manual release valve, comprising check valve means normally closing exhaust of reservoir air from said system; trip means for said check valve means; handle means arranged for manual actuation; and a delayed return mechanism interposed between and operably interconnecting said handle means and said trip means, said delayed return mechanism comprising a housing having a fluid-sealed section; a rigid actuating rod extending longitudinally through said housing and beyond said fluid-sealed section at opposite ends thereof, said rod interconnecting the handle means 70 and the trip means; a plunger fixed to said actu-

ating rod and slidably within said fluid-sealed section thereof as a cylinder; a hydraulic fluid within said fluid-sealed section of the housing; free flow passage means extending from one end to the opposite end of said plunger for accommodating passage of hydraulic fluid during movement of the plunger, check means associated with said passage means for permitting fluid flow in only one direction; and restricted passage means also extending from one end to the opposite end of said plunger, for accommodating a considerably lesser flow of hydraulic fluid during movement of the plunger.

2. The combination recited in claim 1, wherein in the housing is made up of two tubular sections removably fastened together end-to-end; wherein a cylinder for the plunger is defined by one of said sections, and a mounting for the handle means by the other; and wherein cylinder-sealing means are interposed between the interiors of the two sections, dividing one from the other.

3. The combination recited in claim 2, wherein the check valve means controlling exhaust of reservoir air from the system are disposed in a housing having an annular projection extending opposite the trip means; wherein the free end of the cylinder section of the delayed-return mechanism is removably attached to said annular projection; wherein cylinder-sealing means are interposed between said end of the cylinder section and said annular projection; and wherein the actuating rod extends slidably through the sealing means at opposite ends of said cylinder, into connection with said trip means at one of its ends, and into connections with said handle means at its opposite end.

4. The combination recited in claim 3, wherein in the free flow passage means are relatively large bore passages extending through the body of the plunger; and wherein relatively slight clearance between the plunger and the walls of the cylinder in which it slides provides said restricted passage means.

5. The combination recited in claim 4, where- 45

in the handle means comprises a stem having a disk crown, and wherein the actuating rod is arranged as a push-rod, with its one end abutting against the trip means, and its opposite end abutting against the superficial surface of the disk crown of said handle means.

6. The combination recited in claim 5, wherein in an annular insert is positioned at the free end of the handle-mounting housing section for 10 retaining the handle means in operative position, the disk crown of said handle means being disposed within said housing section, and the stem thereof extending from said housing section through said annular insert.

7. Delayed-return, valve-actuating mechanism, comprising a cylindrical housing having a portion of its length fluid-sealed as a hydraulic cylinder, one end portion formed as a housing for actuating handle means, and the opposite end portion formed for connection to valve structure; a push-rod extending longitudinally through said fluid-sealed portion of the housing and beyond, into said end portions of the housing, for longitudinal sliding movement; a hydraulic fluid 20 within said cylinder; a plunger fixed to said push-rod within said cylinder; free flow passage means extending from one end to the opposite end of said plunger for accommodating passage of hydraulic fluid during movement of the plunger; check means associated with said passage means, said check means being arranged to permit fluid flow only toward said one end portion of the housing; restricted passage means also extending from one end to the opposite end of said plunger, 25 for accommodating a considerably lesser flow of hydraulic fluid during movement of the plunger; and actuating handle means operably mounted within and extending from the free end of said one end portion of the housing.

JAMES F. WADE.
